UNITED STATES PATENT OFFICE

162,194

WHEEL COVER OR SIMILAR ARTICLE

George Albert Lyon, Detroit, Mich.

Application December 28, 1949, Serial No. 6,877

Term of patent 14 years

(Cl. D14—30)

To all whom it may concern:

Be it known that I, George Albert Lyon, a citizen of the United States, and a resident of the city of Detroit, in the county of Wayne and State of Michigan, have invented a new, original, and ornamental Design for a Wheel Cover or Similar Article, of which the following is a specification, reference being had to the accompanying drawing, forming a part thereof.

On the drawing:

Figure 1 is a side elevational view of a cover, embodying the present design;

Figure 2 is a diametrical profile view of the cover; and

Figure 3 is a fragmentary perspective view of the cover.

The dash outline showing in Figures 1 and 2

represents a conventional wheel and tire assembly with which the cover may be used, and is for illustrative purposes only.

I claim:

The ornamental design for a wheel cover, or similar article, as shown and described.

GEORGE ALBERT LYON.
